DESIGN FOR A TOBACCO PIPE OR SIMILAR ARTICLE

Floyd Snyder, Cincinnati, Ohio, assignor to Floyd
Snyder Pipes Inc., Milford, Ohio, a corporation of Ohio

Application December 22, 1945, Serial No. 125,008

Term of patent 14 years

(Cl. D85—8)

To all whom it may concern:

Be it known that I, Floyd Snyder, a citizen of the United States and a resident of Cincinnati, in the county of Hamilton and the State of Ohio, have invented a new, original, and ornamental Design for a Tobacco Pipe or Similar Article, of which the following is a specification, reference being made to the accompanying drawing, forming a part thereof.

Fig. 1 is a side elevational view of a tobacco pipe or similar article, showing my new design.

Fig. 2 is a top plan view of the pipe shown in Fig. 1.

Fig. 3 is a bottom plan view of the pipe shown in Fig. 1.

Fig. 4 is a front elevational view of said pipe.

Fig. 5 is a rear elevational view of said pipe.

I claim:

The ornamental design for a tobacco pipe or similar article, substantially as shown.

FLOYD SNYDER.
